Attorney

UNITED STATES PATENT OFFICE

CARL ARNOLD, OF NURMBERG, GERMANY

SIREN TOY WITH SPARK PRODUCING DEVICE

Application filed June 18, 1932, Serial No. 617,964, and in Germany February 24, 1932.

This invention relates to a toy with siren and spark producing device actuated by a rack driving mechanism.

Siren toys for this purpose are already known which are operated by placing in the mouth and blowing air therein. These measures for producing sounds were not perfect from a hygienic point of view. The spark beams could not be produced in conjunction with the siren sound. These objections are overcome by the toy hereinafter described.

An embodiment of the invention is illustrated by way of example in the accompanying drawing in which:—

15 Figure 1 shows the toy in side elevation partly in section.

Figure 2 shows the siren in top plan view, one half with the top plate removed, and, in section in the other half.

20 Figure 3 is a top plan view of the emery wheel fixing device.

Above a known rack driving mechanism *a*, or the like, provided with returning spring, a casing, cap *c* or the like, is arranged, which 25 has air-holes *b*, and is partly closed by a cover *f* likewise having an air-hole *d*. In the interior of this casing *c* a second casing *i* having air-holes *h* is mounted on the driving mechanism shaft *b*. Any desired number of fan 30 blades *k* of any suitable shape are fixed on the interior of the casing *i*. The blades *k* cause rotation of the casing *i*. Flaps *l* are likewise fixed on the driving mechanism shaft *g*, and carry oscillatably mounted cerium 35 stone levers *m* which are gyrated by the shaft *g*. The cerium stones carried by the levers *m* bear against an emery wheel *n* loosely mounted on the shaft *g*. The emery wheel *n* must be loosely mounted in order not to im-

40 pair the rapid movement of the cerium stone levers and of the blades of the siren, which is necessary for producing the sparks and the sounds. In order, during the gyrating movement of the oscillating levers, not to impart a 45 too rapid rotary movement to the loosely mounted emery wheel owing to the friction produced between the wheel and the rotating shaft, which movement would prevent the production of the sparks, a flap *o* is provided 50 on the upper side of the siren and carries a

strip of soft material such as rubber, cardboard or the like. This strip *p* bears against the emery disc during the production of the sparks and only allows the wheel to rotate slowly. Intensive sparking is thus produced. 55 Bridges fixed on the siren carry a disc *q* shaped as a head or the like and provided with windows. The sparks produced pass through these windows or illuminate same in the event of coloured transparent panes being affixed 60 thereunder.

The toy operates in the following manner: By exerting pressure on the rack of the driving mechanism the shaft *g* is rapidly rotated together with the casing *i* fixed thereon. Owing to the rotation air will be drawn through the cover hole *d* and propelled by the blades *k* towards the holes *h* in the rotary casing *i*. The air flows out from these holes through the holes *b* of the stationary casing *c*. A siren like noise is thus produced which can be made louder or feebler by varying the pressure exerted on the rack. At the same time as the siren is sounded, the spark producing device *l, m, n* connected to the driving 70 mechanism shaft is operated. 75

I claim:—

1. A siren comprising in combination a rack driving mechanism having a returning spring, a stationary casing provided with air-holes fixed on said mechanism, a cover on said casing, a driving shaft in said mechanism, a rotary casing provided with air-holes fixed on said shaft and surrounded by 80 said stationary casing, and blades on the interior of said rotatable casing adapted to draw air into said rotatable casing and to expel same through the holes in said stationary casing to produce a siren like noise. 85

2. A siren toy as specified in claim 1, comprising in combination with the stationary siren casing and the shaft, oscillatable levers carrying cerium stones fixed on said shaft above said casing, an emery wheel loosely mounted on said shaft adapted to co-act with 90 said cerium stones to produce sparks during the rotation of said shaft and the production of the siren like noise. 95

3. A siren toy as specified in claim 1, comprising in combination with the station- 100

ary siren casing and the shaft, oscillatable levers carrying cerium stones fixed on said shaft above said casing, an emery wheel loosely mounted on said shaft adapted to co-act with said cerium stones to produce sparks during the rotation of said shaft and the production of the siren like noise, a flap on the upper side of said casing, and a strip of soft material carried by said flap adapted to bear against said emery wheel to brake said wheel and to ensure relative movement between said cerium stones and said wheel.

In testimony whereof I affix my signature.

CARL ARNOLD.
